ADJUSTABLE CELL-CASE OR PARTITION MACHINE

Walter E. Jensen, Chicago, Ill., assignor, by mesne assignments, to F. J. Kress Box Company, Pittsburgh, Pa., a corporation of Pennsylvania

Application September 18, 1935, Serial No. 41,118

19 Claims. (Cl. 93—37)

The present invention relates to machines for manufacturing structures of heavy paper stock or similar material comprising strips crossing and interlocked with each other; and, it has for its object to produce a simple and novel machine adapted to be easily adjusted to produce structures varying widely as to the number, the spacing and the height of the strips of which they are composed.

10 Machines of this general type are composed of various mechanisms and groups of mechanisms, each serving a definite purpose; and, as these mechanisms in my improved machine in themselves contain features of novelty, the invention 15 may, in some aspects, be regarded as having for some of its objects the creation of improved mechanisms capable of more general uses although particularly adapted for use in cell case machines or the like.

20 The various features of novelty whereby my invention is characterized will hereinafter be pointed out with particularity in the claims; but, for a full understanding of my invention and of its objects and advantages, reference may be 25 had to the following detailed description taken in connection with the accompanying drawings, wherein:

Figures 1, 2 and 3 are, respectively, side views and a front or end view of a machine embodying the present invention; Fig. 4 is a vertical, longitudinal section, on a larger scale, showing only a part of the machine; Fig. 5 is a perspective view showing, more or less diagrammatically, the making and the assembly of two sets of strips, three in each set; Fig. 6 is a vertical, longitudinal section through the punch apparatus for punching the sheet that travels horizontally through the machine; Fig. 7 is a section, on line 1—7 of Fig. 6, parts being broken away; Fig. 8 is a section on line 8—8 of Fig. 7, showing only the punch and a fragment of its support; Fig. 9 is a bottom plan view of the plunger element of the punch; Fig. 10 is an elevation, on a larger scale than Fig. 1, of the parts that reciprocate the rack bar which drives one end of the upper feed rollers; Fig. 11 is a section on line 11—11 of Fig. 10, a fragment of the frame of the machine being shown; Fig. 12 is a view, partly in plan and partly in section, illustrating the mechanism for sawing notches in the edges of the vertically-movable ribbons and the relation of this mechanism to the stock or material that is fed horizontally; Fig. 13 is a section, on a larger scale, on line 13—13 of Fig. 12; Fig. 14 is a view, similar to Fig. 12, showing only a fragment of one of the

ribbon holders or guides, with a ribbon therein, and a fragment of the saw with dotted lines showing the paths of the saw teeth during a stroke of the saw; Fig. 15 is a section on line 15—15 of Fig. 14; Fig. 16 is a vertical section, on a plane extending lengthwise of the machine, through the shearing means cutting pieces off the lower ends of the vertically-movable ribbons and the adjacent guiding and feeding means; Fig. 17 is a view that is in part a section on line 17—17 of Fig. 16 and in part an elevation of the structure shown in the latter figure; Figs. 18, 19 and 20 are bottom plan views of the shears and the operating bar therefor, appearing in Figs. 16 and 17, illustrating different positions of the parts; Fig. 21 is a section on line 21—21 of Fig. 20; Fig. 22 is a plan view of the securing means for the pins that hold the movable shear blade of Figs. 16—21 against the stationary shear member and guide it in its movements; Fig. 23 is a rear elevation of a fragment of the nest of power-driven spindles to which the little feed rollers in Figs. 16 and 17 are connected or adapted to be connected; Fig. 24 is a section, on a larger scale, on line 24—24 of Fig. 23; Fig. 25 is an elevation of a fragment of the structure shown in Fig. 24, showing a flexible shaft connected to one of the spindles shown in Fig. 24 and a second flexible shaft partially connected to the other of the spindles; Fig. 26 is a view of the shaft for the driven upper feed roll, showing the immediate driving means which, at one end of the shaft, appears in elevation, and at the other end, where there is a clutch, is in section; Fig. 27 is a section, on a larger scale, on line 27—27 of Fig. 26, through the clutch, only a fragment of the clutch being shown; Fig. 28 is a plan view of the inner end of the clutch shifting bar present in Figs. 26 and 27, showing in full and dotted lines the relation between the bar and the pin actuated thereby in the "on" and "off" positions, respectively; Fig. 29 is a section, on a larger scale, on line 29—29 of Fig. 1, showing the driving means for the controller for the shears that sever the vertically-fed ribbons and the controller for the clutch associated with the upper feed rolls; Fig. 30 is a view, partly in section and partly in side elevation, of the controllers to which reference has just been made; Fig. 31 is a section on line 31—31 of Fig. 30, showing only the bar for actuating the shears and the actuator for the bar; Fig. 32 is a view similar to Fig. 31, with the parts in different positions, however; Fig. 33 may be said to be a section on line 31—31 of Fig. 30, showing only the clutch-controlling devices; 55

Fig. 34 is a bottom plan view of the disk or wheel appearing in Figs. 31-33; Fig. 35 is a top plan view of the peripheral block or dog, shown on the wheel in Fig. 33, removed from the wheel; and Fig. 36 is a view similar to Fig. 35, showing another form of block or dog.

The machine which I have illustrated is of the type adapted to operate on two sheets of heavy paper stock which are progressively fed and worked until they meet and are interlocked. Usually in such machines one of the sheets travels horizontally and is slit into longitudinal strips that are set on edge; while the other sheet is fed downward from above and is consumed by cutting narrow transverse strips, one at a time, from the advance end. In my improved machine, this situation is reversed, the horizontally-travelling material remaining in sheet form except as transverse strips are severed from the advance end, while the other sheet is divided into ribbons which are fed downward across the path of the horizontal sheet. Thus, as best shown in Fig. 5, there is a horizontal sheet A which is fed forward, step by step, and provided with punched holes, *a*, during its progress; and there is a second sheet B which enters at the top of the machine, travels forward a short distance while being slit longitudinally into ribbons C, which are then twisted through angles of ninety degrees and fed downward in paths at right angles to the plane of the sheet A. Notches *c* are cut into the rear edges of the ribbons and the advance end of the sheet A is forced into these notches. After the advance end of the sheet A has seated itself in the notches in the ribbons, a transverse cut is made across the sheet A to sever therefrom a strip D. These cuts are so placed as to come along the forward ends of a transverse row of holes, *a*, and thus convert these holes into notches opening out through the forward edge of the sheet. The notches in the sheet A are so spaced that each registers with one of the ribbons C. After a sufficient number of strips D have been engaged with the ribbons, the interlocked sections E of the ribbons are cut off, thus producing a product composed of one or more strips E and one or more strips D.

The various mechanisms of which the machine is composed are mounted on a suitable heavy frame which may be said roughly to consist of a hollow lower or base member 1, and an upper member 2 taking more or less the form of an inverted U.

The mechanisms operating on the sheet A are best shown in Fig. 4. Referring to this figure, 3 represents a suitable horizontal table at the rear end of the machine, over which table the sheet passes through edge-trimming means. The edge-trimming means are shown as comprising a transverse roller 4 above the sheet and cutter disks 5 below the sheet. Each cutter disk is rotatably mounted on the end of a lever 6 pivoted, between its ends, as at 1, to a short arm 8 fixed to and radiating from a transverse rock shaft 9. The arm 8 may be part of a bracket having a second, longer arm 10. Between the arm 10 and the lever 6 is a compression spring 12. Fixed to the shaft 9 is a toothed segment 13 meshing with a worm 14 on a longitudinal shaft 15 having thereon, at the rear end of the machine, a hand wheel 16, as shown in Figs. 1 and 2. By turning the hand wheel in one direction, the cutter disks are pressed against the roller 4, being yieldingly held there by the springs 12. Either of the cutters, if there are only two trimming cutters, or any one of them, if there are more than

two, may be swung back into an idle position by grasping the lower end of its lever 6 and swinging the lever in a direction to compress the corresponding spring. By turning the hand wheel in the opposite direction, both or all of the cutter disks are swung away from the cooperating roller.

From the trimming mechanism the sheet travels over the bed 17 of a punch unit mounted on top of the base member 1 of the frame behind the upright frame member for sliding movements from and toward the latter. Above the bed 17 is the vertically-movable cross beam of the punch apparatus. From the punch, where are punched the elongated holes, *a*, as will hereinafter be explained, the sheet passes along to and between a pair of transverse feed rolls 19 and 20 mounted between the two rear portions of the upright sections of the frame member 2. From the feed rolls the sheet passes under a heavy transverse bar or beam 22 carrying the stationary cutting blade 23 of a shearing means; the cooperating blade 24 lying below the plane of the sheet and at an angle of about forty-five degrees with respect thereto. The movable shear blade 24 is fixed upon a heavy cross bar or beam 25 which is movable bodily in a plane extending upwardly and forwardly at an angle of forty-five degrees to the plane of the sheet; whereby the cutting edge at the top of the movable blade cooperates with the shearing edge along the bottom of the stationary blade to sever a strip from the advance end of the sheet A, whenever the movable blade makes an upward stroke.

The punch mechanism is driven from a main transverse shaft 26 from which, together with a second parallel main shaft 27, all of the moving parts receive their power. The shaft 26 has thereon a large gear wheel 28 shown as meshing with a pinion 29 of a well known type of drive mechanism 30 operated by a power input shaft 32; and there is on the shaft 26 a second gear wheel 33 meshing with a similar wheel 34 on the second main shaft 27. Therefore the two main shafts rotate in opposite directions but at the same speed, whenever the machine is running. Two eccentric rods, 35 and 36, one shown in Fig. 4 and the other in Fig. 7, extend from eccentrics 37 on the main shaft 26 to the vertically-movable upper member 18 of the punch unit, whereby the punches are moved up and down once during each revolution of this main shaft. Because the punch unit is adjustable longitudinally of the machine, it is desirable that the eccentric rods be adjustable lengthwise to compensate for the shifting of the rods occasioned by such adjustments. In the arrangement shown, as best seen in Fig. 7, each eccentric rod is connected to the movable punch unit member 18 by a pin 38 having thereon an eccentric 39. By turning this pin the axis of the eccentric 39 may be moved a limited distance from or toward the main shaft 26.

The means for bodily adjusting the punch unit is best shown in Figs. 6 and 7. It will be seen that the bed member 17 has flange-like foot members 40 resting on top of and slidably along the side walls of the hollow base 1. In the top of each of these side walls is a T slot 42 parallel to the longitudinal center line of the machine. The heads of bolts 43, passing through the flanges 40, are slidably engaged in the slots 42. When the nuts 44 on the upper ends of the bolts are tightened the flanges are clamped securely to the main frame member 1. Fixed upon the tops

of the side walls of the main frame are rack bars 45 arranged beside and parallel to the slots 42. The bed 17 of the punch unit has a transverse rotatable shaft 46 provided with pinions 47 meshing with the rack bars 45. After the nuts 44 have been loosened, the shaft 46 may be turned by a hand wheel 48 or the like, shown in Fig. 1, and the punch unit be shifted bodily lengthwise of the machine.

10 The punching elements that actually cut out the material from the paper stock to produce the elongated holes may be, in the main, similar to those heretofore used, comprising lower stationary die members and upper reciprocable punches, 15 each individually adjustable crosswise of the machine; the die blocks having properly shaped slots into which reciprocable punches are adapted to enter. In accordance with my invention, I provide certain improvements which make it 20 possible for the same dies and punches to be used in punching holes of any desired lengths within comparatively wide limits. To this end, as best shown in Figs. 6-9, I make the slots 50 in the die blocks 49 as long as the longest hole 25 which is to be punched during the use of the machine; the length of the hole that actually is punched at any given time being determined by the cooperating punch. The holes, *a*, are shown as being long, narrow slots enlarged at one end 30 into a triangular shape, and the slots 50 in the dies are of similar shape. The punch devices are not simple plungers but composite structures each shown as being composed of a block 52 held up against the under face of the bar or beam 18 by two fastenings, one of which is simply a screw 53 and the other a cutting or punching bar 54. The punching bar extends freely down through the block 52 to a point considerably below the latter. The projecting lower end 55 35 of the punching bar is fashioned into an effective punch of the proper cross section efficiently to cooperate with the enlarged end of the die opening to cut out of the stock the enlarged end of one of the slot-like holes, *a*. The bar 54 has a slot 56 extending through the same at some distance above the lower end and, slidably fitting this slot is a long blade 57. The block 52 has a deep, narrow groove 58 cut into the same from below to receive the upper part of the blade 57.

40 The upper end of the punch 54 is screw-threaded, as indicated at 59, and has thereon a nut 60. With the blade 57 in position, the tightening of the nut 60 causes the blade to be drawn up and clamped in the block 52, and the block to be 45 clamped to the beam 18. The blade 57 is just thin enough to enter one of the slots 50 and is preferably somewhat longer than the slot. The parts are, of course, so proportioned that the blade registers exactly with the slot in the corresponding die when clamped in place. The parts are further so proportioned that the lower edge 50 of the blade 57, which is the cutting edge, forms an acute angle with a horizontal plane. The result is that only that part of the cutting edge 55 of the blade projecting to the right from the punch 55, as viewed in Figs. 6 and 8, can enter the die opening; so that the length of the slot-like hole to be punched in the work will depend on the extent of the projection of the blade from 60 the punch, and the same blade will serve to help cut long or short holes.

It is desirable that the blade members of all of the punch devices be simultaneously adjustable. I have therefore provided the blades 57 75 with rack teeth 62 along their upper edges and

have perforated the blocks 52 at the tops of the grooves therein for the reception of a long transverse shaft 63 whose cross-sectional contour is that of a pinion adapted to mesh with the rack teeth on one of the blades. The punch bars are 5 shown as having cap nuts 64 on their upper ends to limit the distance through which the blades can be lowered by simply loosening the nuts 60, and thus prevent the rack teeth on the blades from becoming accidentally disengaged from the 10 toothed shaft 63 when the nuts 60 are loosened to permit an adjustment to be made. It will thus be seen that, after the nuts 60 have been loosened, all of the blades may be shifted lengthwise 15 in the same direction and through equal distances, by the mere turning of the shaft 63. The shaft 63 may be operated in any suitable way. In the arrangement shown, there is at each side of the machine a rack bar 65 carried by the beam 18 and extending across the top of and at right 20 angles to the shaft 63; the rack bars meshing with the teeth on the shaft. These rack bars mesh with pinions 66 on a transverse shaft 67 extending along the rear side of the beam 18. On one end of the shaft 67, easily accessible to 25 an operator standing beside the machine, is a hand wheel 68 for turning the shaft and thus adjusting the blade members of the punches.

Only the lower feed roll 20, of the two that move the sheet A, is positively driven, power 30 therefor being derived from the main shaft 26. Since this drive is substantially the same as that employed in connection with the upper feed rolls, and which is illustrated in greater detail in the drawings, further description will be given after 35 the drive for the upper feed rolls has been described in detail.

There remains to be explained only one other piece of mechanism which has to do with the sheet A, alone, namely, the shear mechanism including the blades or cutters 23 and 24. This mechanism is substantially the same as that in common use for cutting transverse strips from the advance end of one of two sheets that are being worked up into a cellular structure. It need 40 only be noted that the beam 25 which carries the movable shear member 24 has enlarged, hub-like ends 69 fitting slidably upon sturdy cylindrical posts 70 set at an angle of forty-five degrees and having their central axes lying in vertical planes 45 extending lengthwise of the machine. On each side of the machine is an eccentric rod 72 connected at its forward, upper end to the corresponding hub-like part 69 of the shears. These rods are associated with eccentrics 73, on the 50 shaft 26, one of which is visible in Fig. 2. Thus, just as the movable member of the punch unit is moved up and down once during each revolution of the shaft 26 so, also, are the shears that cut strips from the sheet A opened and again closed 55 during each such revolution.

The mechanisms operating to work up the sheet B will now be described.

The sheet B enters the machine across a table 74 at the very top of and toward the rear of the 60 machine. From the table the sheet passes through slitting mechanism, best shown in Fig. 5, that may be substantially like that heretofore described; there being a transverse roller 75 similar to the roller 4 and slitting cutters 76 co-operating therewith. The shaft 77, the brackets having the arms 78 and 79, the levers 80 and the springs 82, are substantial counterparts of the corresponding elements 9, 8 and 10, 6, and 12 of the trimming means for the sheet A. On one 75

end of the shaft 77, as shown in Fig. 1, there is a gear wheel 83 that meshes with a worm 84 on a shaft 85. The shaft 85 has thereon a hand wheel 86 for turning the same. There may be 5 any desired number of cutting disks of which all or any part thereof may be in use at any one time. Any disk may be held in an idle position in any suitable way. In the arrangement shown, each of the compression springs 82 surrounds a 10 rod 87 hinged at one end to the corresponding lever 80 and extending freely through the bracket arm 79. On the arm 79, beside the rod 87, is a movable dog 88 which is adapted to be slipped under a nut or head 89 on the free end of the rod 15 and thereby hold the corresponding slitting disk away from the work. It will also be obvious that the disk-supporting brackets may be adjusted lengthwise of the shaft 77 to vary the width of the ribbons to be produced. In the arrangement 20 shown, each bracket is slideable lengthwise of the supporting shaft and is adapted to be secured at any point along the shaft by a set screw 90.

The ribbons C into which the sheet B is cut pass down between a pair of feed rolls 92 and 25 93 of which the roll 93 alone is positively driven. The roll 92 is normally pressed against the roll 93 by springs 94. Although these feed rolls, as can be seen in Fig. 3, as well as the rolls 19 and 20, consist of cylindrical shells surrounding and 30 mounted on shafts, I shall not herein distinguish between a roll and its shaft, since the construction is well known.

The roll 93 has two drives to turn it step by step so that, providing proper controlling means, 35 the drives may be caused to alternate with each other and produce different combinations of steps than if only one drive were employed. For example, in a cell case wherein the cells are of equal length, the combined lengths of two corresponding end projections of the strips, or buffers, at opposite ends of the structure would always be equal to a cell length if the ribbons were always fed step by step through steps of one length only. If a buffer is to be of some other length, the step 40 through which the ribbons are fed to provide the buffer material must be lengthened or shortened, as the case may be. I therefore provide two drives each containing a clutch and control one of the clutches that it may be automatically 45 thrown in and out. Assuming that the drive containing the latter clutch will turn the feed roll through a greater angle than does the other drive then, when that clutch is in, the ribbons are fed through a longer step than when that clutch 50 is out; it being, of course, understood that the roll simply overruns the clutch of the one drive whenever the drive that feeds the ribbons through longer steps is active.

The feed roll 93 with the clutches is best shown 55 in Figs. 26 to 28. The reduced end portions 95 and 96 of the feed roll shaft are journaled in the upper ends of the vertical elements of the upper main frame member or section 2. On the part 95 is any suitable clutch 97 adapted to be driven by 60 a reciprocable rack 98 so as to drive the roll on each downward stroke of the rack and permit the roll to stand still during each upstroke of the rack. Any usual or suitable clutch of this kind, which permits the member driven thereby, in this 65 case the feed roll, to be turned freely at any speed faster than that at which the clutch tends to drive it, may be employed. On the other end of the shaft of the roll is the clutch which is to be automatically controlled. This clutch comprises 70 75 a cylindrical housing 99 fixed to the shaft, a

driving sleeve 100 surrounding and rotatable on the end section 96 of the shaft, and clutch dogs 102. The clutch dogs each consist of a little block lying between and pinned to a pair of large rings 103 surrounding the driving sleeve 100 within the clutch housing. The pins 104, which secure the dogs to the rings, serve as axles upon which the dogs may turn. That part of the driving sleeve that projects into the clutch housing has peripheral gear teeth 105. Each clutch dog 10 has an inner section 106 in the shape of a segment of a pinion meshing with the teeth 105, whereas the outer half or section 107 of each dog is a cam adapted to cooperate with the interior of the cylindrical wall of the clutch housing. Thus, 15 when the sleeve 100 is turned in the clockwise direction, as viewed in Fig. 27, the dog there shown will tend to rock in the counter clockwise direction, and its cam portion will bind against the surrounding wall of the clutch housing and 20 the housing will be positively driven. When the driving sleeve turns in the opposite direction, the dogs are rotated about their axles to carry their cam faces away from the cylindrical wall of the housing and the latter and the feed 25 roll as a whole will no longer be driven. The driving sleeve 100 is oscillated by a rack bar 108, similar to the rack bar 98, meshing with a pinion 109 fixed to the driving sleeve; the rack bar being 30 held in mesh with the pinion by a suitable keeper 110. It will be evident that the clutch 97 may be like the clutch just described and be driven in exactly the same way by the rack bar 98.

It will be seen that if the rings 103 be turned 35 slightly in the clockwise direction, as viewed in Fig. 27, relatively to the driving sleeve, the clutch dogs will rock in the clockwise direction and release themselves from the clutch housing. Means are provided to accomplish this. The driving sleeve has a longitudinal, peripheral groove 112 40 in which is slidably fitted a long bar 113. The inner end of the bar is cut off on a diagonal line, as indicated at 115 in Fig. 28. Fixed to the dog-carrying rings 103 is a pin 116 extending inwardly toward the axis of the clutch into the path of 45 the inclined end of the bar 113. Normally, when the parts are in clutching positions, as in Fig. 27, the pin and the bar 113 are positioned relatively to each other, as shown in full lines in Fig. 28. When the bar 113 is pushed in, bringing it into 50 the dotted line position in Fig. 28, the pin 116 is pushed sidewise into the dotted line position in Fig. 28; or, in other words, the rings 103 are turned through a small angle in the clockwise direction, as viewed in Fig. 27. On the outer end 55 of the sleeve is a loose ring 114 fastened to the outer end of the bar 113 having therein a peripheral groove extending around the same. The ring 114 is fastened to the bar 113. The bar may be shifted endwise by suitable means engaged in 60 the groove in the ring 114. In the arrangement shown, there is pivotally mounted on the frame 2 a bell crank lever one arm 117 of which is forked so as to straddle the ring 114. The arm 117 is 65 provided with suitable means, such as a ring 118, for example, lying loosely in the groove in the ring 114 to enable the lever to move the ring lengthwise of the feed roll shaft. A spring 119 acts on the second arm, 120, of the bell crank lever in a direction yieldingly to hold the bar 113 70 in its retracted position which permits the clutch to operate. The arm 120 is connected to the plunger 122 of a solenoid 123, preferably by a tension spring 124. When the solenoid is energized the arm 120 is drawn down, as viewed in 75

Fig. 26, and the bar 113 is pushed toward the left, causing the clutch to be placed in an idle condition. Consequently, as long as the solenoid remains deenergized, the clutch controlled thereby is operative to drive the feed roll and, when and while the solenoid is deenergized, the feed roll cannot be driven by this clutch. The means for controlling the solenoid will be described later.

The means for actuating the rack bar 108 are illustrated in Figs. 1, 10 and 11. There is a transverse shaft 125 extending across the machine near the main shaft 27. On one end of the shaft 125 is fixed a rocker member 126 which has two wide slots or channels, 127 and 128, arranged radial to the axis of the shaft and at an obtuse angle to each other. Slidable in the slot 127 is a block 129 which may be shifted into any desired position along the slot and be held there by a screw device 130. A pin 132 secures the lower end of the rack bar 108 to the block 129. The part of the rocker that contains the slot or channel 128 extends across the outer face of a disk 133 fixed on the adjacent end of the main shaft 27. On this disk is a crank pin 134 engaged in the slot 128. Therefore, as the shaft 27 revolves, the rocker is oscillated and the rack bar is reciprocated. The length of stroke of the rack bar is determined by the position of the block 129 in its slot or channel and is varied by shifting the block along the channel. The shaft 27, when the machine is in operation, revolves in the clockwise direction, as viewed in Fig. 10. It will be seen that the down stroke of the rack bar, from the full line position to the dotted line position, which is the working stroke, is effected during the time the main shaft turns through an angle of one hundred and ten degrees. In other words, the feeding stroke, during which the ribbons move, is a quick one; while the return stroke, during which the ribbons are at rest, is relatively slow and thus affords ample time for those operations which must be performed while the ribbons are stationary. The shafts 27 and 125 have on their ends, at the opposite side of the machine, actuating means for the rack bar 98 that are identical with that for the rack bar 108 just described and corresponding parts of these actuating means are identified in the main views of the drawings by the same reference characters. The two rockers are placed in exactly the same positions angularly of the shaft 125, so that rack bars 98 and 108 move in unison with each other. When the steps through which the ribbons are to be fed are not all of the same length, the blocks 129 in the actuating means for the bars are so set that the bar 98 serves to feed the ribbons through the shorter steps while the longer steps are taken care of by the bar 108.

As heretofore explained, the feed roll 20 of the pair that moves the sheet A is driven step by step by actuating means similar to that just described in connection with the upper feed rolls. As shown in Fig. 1, the feed roll 20 is driven by a rack bar 135 connected to a rocker device 136 associated with a disk 137 on the main shaft 26 in just the same way that the rockers which reciprocate the bars 98 and 108 are associated with the disks 133 on the shaft 27; the rocker device 136 being set at such an angle, however, that the sheet A is fed while the ribbons are stationary.

The ribbons, after leaving the upper feed rolls and being twisted to meet the sheet A edge to edge, pass through a secondary feeding means and guides or holders that register them accurately with the slots or notches in the advance

edge of the sheet A. These devices, together with shear means to sever the ribbons transversely, are carried by an auxiliary rigid frame 140 mounted between the sides of the upper main frame member 2, as shown in Figs. 1, 2 and 3. The auxiliary frame is movable vertically on rigid guide rods 141 and 142 fixed to the main frame and effectively holding the auxiliary frame against movements in any direction except up and down. Also, the auxiliary frame has a heavy ear or lug 143 fitted slidably on a vertical, rotatable shaft 144. The auxiliary frame is adapted to be raised and lowered by means of two vertical shafts 145, 145 at opposite sides of the machine, these shafts being mounted on the main frame above the auxiliary frame so as to be rotatable while being held against lengthwise movements. The lower ends of the shafts 145 are screwed into the auxiliary frame, so that the mere act of turning the shafts raises or lowers the auxiliary frame. On the upper end of each shaft 145 is a bevel pinion 146 meshing with a complementary pinion 147 on a transverse shaft 148. On one end of the shaft 148 is a handle or crank 149 for turning the same. Thus, by operating this crank or handle the auxiliary frame may be raised or lowered.

The details of the mechanisms mounted on the auxiliary frame are illustrated in Figs. 16 to 25. On the rear part of the auxiliary frame is mounted a motor 151. On the auxiliary frame or forming a part thereof, just below the motor is a transverse elongated gear casing 152 within which are two horizontal rows of pinions, those in the upper row being indicated at 153 and those in the lower row at 154. The pinions in one row are staggered with respect to those in the other row, and each pinion meshes with two pinions in the opposite row. The shafts of three of the pinions are extended through the rear wall of the casing, as indicated at 155 and are there provided with sprocket wheels 156; these three pinions being the middle pinion in the upper row and two pinions near the two ends of the lower row. An endless sprocket chain 157 extends from the motor around the three sprocket wheels 156, passing down under the two end wheels and up over the top of the middle wheel. The forward ends of all of the pinion-supporting shafts project out through the front wall of the gear casing, as indicated at 158, and each has therein a deep notch or slot 159 cut into the same through the end face. In front of the gear case, and spaced apart therefrom, is a transverse row of small horizontal auxiliary feed rollers 161 arranged parallel to the longitudinal axis of the machine. These rollers are spaced far enough apart to provide room for a similar roller between adjacent rollers. Each auxiliary roller has attached to the rear end a flexible shaft 162, best shown in Fig. 25. Each flexible shaft has at its free end a rigid part 163 from the free end of which projects a tongue 164 adapted to enter the slot 159 in one of the motor-driven shafts 158. To keep the tongue from slipping laterally out of the slot in which it is seated, each flexible shaft has a sleeve or thimble 165 surrounding the rigid end section and adapted to be drawn back on the shaft proper to expose the tongue. Each flexible shaft may have a sheathing in the form of a coiled spring 166 which abuts at one end against the thimble or sleeve and tends constantly to hold it in its outermost position, as indicated in the upper of the two connections in Fig. 25. The rollers 161 are mounted between

suitable cross bars or supports 167 and 168 fixed on or forming part of the auxiliary frame.

Cooperating with the fixed rollers 166 are similar but loose, removable rollers 169. Each roller 5 169 is rotatably supported on the upper end of a flat open-ended sheet metal shell 171 which is hinged at its lower end to the top of a block 127, as indicated at 173. Each block 172 has a narrow passage 174 extending vertically 10 through the same at the base of the shell thereon and parallel with the auxiliary feed rollers. There are as many of the blocks 172 as the maximum number of ribbons which it may be desired to work up at any given time. Each of 15 these blocks, as best shown in Figs. 16 and 21, has a forward extension 175 underlying a flat horizontal foot member 176 on the roller-supporting bar 167. The member 176 has a long slot 177 extending substantially across the width 20 of the machine. Each block is secured to the member 176 by a bolt 178 extending down through the slot 177 into the extension 175. In order to keep the blocks from swinging angularly about the bolts that hold them in place, 25 the frame member 176 is provided with long accurately finished keys or splines 180 lying parallel and on opposite sides of the slot, and the blocks are grooved to fit upon these keys.

Each of the blocks 172 forms one member of 30 a pair of shears, the other member being a flat blade 179 lying flat against the bottom face of the block. Each of the blades 179 has therein two slots 181 and 182. One of these slots has a portion extending lengthwise of the blade on 35 one side of a longitudinal line, and a more or less diagonal portion or section extending across said line; whereas the other slot has a longitudinal portion or section on the opposite side of said line and an inclined section extending therefrom across said line in parallel relation to the inclined 40 section of the other slot. Pins 183 extend through these slots and into or through the block to hold the blade flat against the under side of the block and yet permit it to move in its own plane. The parts are so proportioned that when 45 the pins are at what may be termed the rear ends of the slots, as indicated in Fig. 20, the cutting edge of the blade lies just beside the passage 174 in the block. Consequently, a ribbon may be fed down through this passage without encountering 50 any interference on the part of the movable shearing blade. When the shearing blade is moved so as to bring the opposite ends of the slots therein toward the pins, the blade is subjected 55 to a swinging motion causing its cutting edge to extend diagonally across the lower end of the passage 174, as shown in Fig. 19, and then the blade is again caused to straighten out and extend completely across the passage in the block, as shown in Fig. 18. In moving from the 60 position indicated in Fig. 20 to that of Fig. 18, a ribbon projecting down through the passage in the block is cut in two along a transverse line.

While the pins 183 may take any suitable form, 65 I have shown them as being plain pins each having at one end a head and near its other end an annular groove 184. A spring plate 185, having notched ends to embrace the protruding ends of the pins, lies on top of the block. The plate may be locked to the pins by washers 186 each 70 having cut therefrom a radial section just wide enough to permit the reduced neck portion on one of the pins to pass therethrough; the washers being slipped upon the grooved portions of the pins above the notched ends of the spring 75

plate. Underneath the center of the spring plate is a set screw 187 screwed into the block. By adjusting the set screw, the upward pull of the spring on the pins may be varied, the movable shear blade being at all times yieldingly held 5 against the flat under face of the block.

The movable shear blades are all operated from a transverse reciprocatory bar 188 having therein a groove 189 extending throughout the length thereof. The forward end of each movable shear 10 blade has a pin 191 projecting therefrom into the groove 189. As will hereinafter be explained, the bar 188, in its movements, travels both in the direction of its length and in a direction longitudinal of the machine, the resultant path of 15 movement of any point on the bar being diagonal at an angle of about forty-five degrees.

It will, of course, be understood that the various auxiliary feed rollers, passages or channels, and cutting or shear blades must be long enough 20 or wide enough, as the case may be, to accommodate the widest ribbons which it may be desired to work up in the machine.

In using the machine, the desired number of 25 guide blocks are adjusted along the auxiliary frame so as to bring the ribbon-receiving passages therein in the vertical longitudinal planes of the notches in the advance edge of the oncoming horizontal sheet A. In so adjusting the blocks each has its auxiliary feed roller 169 placed between the nearest pair of fixed feed rollers and coupled to one of the motor driven pinion shafts 158. As best shown in Figs. 16 and 17, there are on the transverse frame members 167 and 168 flat springs 192 which may be brought to bear against 30 the roller supports 193 on the sheet metal guides 171 and thus cause the loose roller to be yieldingly pressed against the proper roller of the pair of fixed rollers between which it lies. It will be seen that the hinged connection between each sheet 35 metal guide and its supporting block permits the roller carried by that unit to be lowered down from between two of the fixed rollers by simply moving the block transversely of the machine and thus increasing the distance between the hinge 40 173 and the space between the two fixed rollers. In the same way, at the time of adjusting the block to a new position, the sheet metal guide member carried thereby is swung down far enough to clear the fixed auxiliary rollers until the loose 45 roller thereon comes opposite the gap through which the ribbon to be handled by that block can most conveniently be fed, and then the sheet metal guide is swung up as the block continues 50 its transverse movement, and the loose roller is 55 placed in the selected gap.

The number of cells in the finished product, counting in one direction, is determined by the 60 number of ribbons delivered at the assembly point; but the number of cells, counting cross-wise of said direction, depends entirely upon the operation of the shearing means for cutting the ribbons. In other words, a single cell case may be as long as the length of ribbon which it is possible to feed, the sheet A supplying all of the 65 cross strips that may be needed. Therefore, unless the number of cells counted lengthwise of the strips cut from the ribbons is to remain fixed, means must be provided to cause the ribbon-severing shears to operate after any desired variable number of cross strips have been interlocked with the ribbons. The means contemplated by the present invention for this purpose will now be described.

The shear actuating bar 188 is driven from the 75

vertical shaft 144 to which reference has heretofore been made. As best shown in Figs. 1 and 3, there is on the shaft 144 a wheel 194, this wheel lying just between the lug or ear 143 on the auxiliary frame and another lug or ear 195 on this same frame. Therefore, as the auxiliary frame moves up and down, the wheel 194 is carried along with it. As shown in Figs. 30 to 32, the wheel 194 is held against rotation on the shaft 144 by a key 196, so that it must revolve with the shaft while free to slide up and down along the same. The wheel has in the periphery any desired number of seats 197 in any one or all of which may be set a lug or lugs 198. The shear 15 blade actuating bar 188 lies in the plane of the wheel 194 and has one end adjacent to the periphery of the latter. On this end of the bar is a roller 199 adapted to be engaged by the lug or lugs as the wheel is rotated. The bar has 20 therein parallel slots 201 extending diagonally to the longitudinal axis of the bar and into these slots extend pins 202 fixed to the auxiliary frame. A spring or springs 203 tends or tend constantly to hold the bar edgewise against the periphery 25 of the wheel. It will thus be seen that as the wheel is revolved, the bar is pushed away against the resistance of the springs by the lug and must, perforce, travel in a diagonal direction on a working stroke; and then, after the lug has passed 30 on, the springs will push the bar back through a return stroke.

If there is only one lug on the wheel 194, the ribbons will be severed once during each revolution of the shaft 144. The particular wheel 35 illustrated has seats for as many as eight lugs. Therefore for each revolution of the shaft there may also be two, four or eight shearing operations, provided the spacing of the cuts is to be uniform.

40 The timing of the shears by the wheel 194 is not the only way in which the shearing operation may be variously coordinated with the operations of the other mechanisms. For example, the timing of the shaft 144 itself may be changed 45 in a simple manner. In the arrangement shown, there are on the lower end of this shaft a battery of ratchet wheels which are numbered from 204 to 209, inclusive. The lower wheel 204 has the largest number of teeth and each other wheel 50 contains a smaller number of teeth than does the wheel immediately below the same. Coaxial with the ratchet wheels is a swinging pawl carrier 211 having a vertical round bar 212 beside and extending throughout the height of the battery 55 of ratchet wheels. Slidable up and down on this bar is a pawl 213 adapted to engage with any one of the ratchet wheels. The several ratchet wheels are spaced apart by intervening disks 214 which project far enough beyond 60 the ratchet teeth to serve as barriers that prevent the pawl from accidentally slipping from one ratchet wheel to another.

The swinging pawl carrier 211 is driven from the main shaft 27. As will be seen from Figs. 65 4 and 29, there is on the shaft 27 a cam 215. The pawl carrier has thereon a toothed segment 216. Engaged with the segment is a rack bar 217 slidable lengthwise through a suitable box-like guide 218 on one of the side walls of 70 the main frame member 1. One end of the rack bar has a roller 219 engaged with the periphery of the cam 215, and it has, also, a fork 220 straddling the shaft 27 and keeping that end from dropping down. The cam drives the rack bar 75 through working strokes and the return strokes

are caused by a compression spring 222 interposed between a lug 223 on the bar and a second lug 224 on the frame. The spring preferably surrounds a long rod 225 fixed to the lug 224 and slidable through the lug 223. Instead of 5 abutting directly against the lug 224, the adjacent end of the spring preferably engages a nut 226 adjustable along the rod 225 and adapted to vary the initial compression of the spring. Thus the pawl carrier is oscillated or rocked 10 through a working stroke and a return stroke once during each revolution of the main shaft, and the shaft 144 is turned through a fraction of a revolution, determined by the particular ratchet wheel with which the pawl happens to be 15 engaged, during this same period.

The wheel 194 may be utilized to control the circuit that energizes the solenoid 123. Fastened to a downward extension 227 from the lug 195 on the vertically-movable auxiliary frame 140 is a 20 switch box 228. On top of the box is a horizontally-swinging switch handle 229 having a roller 230 at its free end. On the under side of the wheel 194 may be secured a segmental switch-operating piece or dog 232 so positioned that 25 as it passes the roller 230 it engages therewith and pushes it outwardly. Assuming the switch to be one which tends constantly to take a closed position, it will be seen that the dog 232 serves to open the switch and hold it open for a period 30 of time corresponding to the angular length of the dog. Fig. 33 shows the switch arm in full lines in the position it occupies when the switch is closed; whereas the switch arm and the dog 35 232 are shown in dotted lines in the positions which they occupy when the switch is open. The dog 232 may be a little curved bar having a flange 233, the curved bar portion being engaged with the periphery of the wheel and the flange underlying the wheel and being secured thereto 40 by screws or other fastenings extending through holes 234 in the flange. The wheel is shown as having in the under side a number of screw holes 235 to receive the holding screws for the switch-operating dog or dogs. It is, of course, 45 obvious that more than one switch-operating dog may be attached to the wheel and that the angular length of the dogs may be anything desired. Thus in Fig. 36 there is shown a dog 236 whose angular length is more than three hundred 50 degrees. When the dog of Figs. 33 and 35 is employed, the ribbons C are fed through a long step only infrequently; whereas, in case such a dog, as shown in Fig. 36, is employed, the majority of the steps will be long ones and short 55 steps will be infrequent. Obviously, any other combination of feeding steps may be obtained by using switch-operating pieces or dogs of still other angular lengths.

I shall now describe the means by which the 60 notches, c, are cut into the rear edges of the ribbons, reference being had particularly to Figures 2, 4, 5, and 12-15 of the drawings.

It will be seen from Fig. 4 that the sheet A passes between a pair of guide plates 237 and 238, 65 one above the sheet and the other below, just before reaching the shears that cut strips therefrom. The lower plate, 238, extends a short distance under the stationary shear bar or beam 22 and, directly in front of the same, and in the same horizontal plane, is a long saw blade 240 extending crosswise of the machine. This saw blade normally lies behind the ribbons when the latter are fed downward, but is adapted to be moved forward to saw notches in the rear edges 70 75

of the ribbons. Just in front of the saw are a series of devices that constitute guides for the ribbons and also guides that yieldingly grip the saw blade while it is cutting into the edges of the ribbons and being withdrawn from the ribbons. Each of these combination guides and grippers comprises three long bar-like members two of which, indicated at 241 and 242, lie flat upon each other and are adapted to be pressed apart by the saw. The third of these members is a flat bar 243 having one of its broad faces directed toward but spaced apart from corresponding edges of the members 241 and 242 to provide a gap 244 through which one of the ribbons may pass. There is a long slot 245 extending from one end of the bar 243 inwardly to a depth at least as great as the deepest saw cut to be made at any time; this slot being in the plane of the meeting faces of the bars 241 and 242. It will thus be seen that while a ribbon is engaged in the gap 244 between the bar 243 and the other two bars, the saw may enter the slot 245 in the bar 243 and between the bars 241 and 242 and thereby cut a notch into the rear edge of the ribbon. The three members of each guiding and gripping device are mounted on a block 246; the bars 242 and 243 being attached at their forward ends to the block so as to be held immovable thereon. The bar 241, on the other hand, is so held that it acts in the manner of a spring clip. In the arrangement shown, the bar 241 being of spring metal, its forward end is fastened to the blocks by a single screw 247; the bar being prevented from swinging about this screw by pins 248 and 249 extending up through the same from the underlying bar 242. On the forward pin 249, which is in front of the holding screw, is a thin washer 250 that serves as a spreader between the forward ends of the two bars. When the screw is tightened, the upper bar is stressed and bent slightly, because of the presence of the washer, and the saw-engaging part thereof is yieldingly pressed down on the underlying bar. There are as many of these combination guiding and gripping units as the maximum number of ribbons that it may be desired to employ; and they are mounted on a reciprocable carrier which moves them into working positions to permit the sawing to be done and then retracts them into idle positions while the sheet A is fed forward and the end thereof is engaged with a set of notches that have just been sawn. This carrier consists of a long casting 252 extending transversely of the machine and provided at its ends with hub-like parts 253, surrounding and slidably fitted on stationary cylindrical guide bars 254; these guide bars being located at opposite sides of and extending longitudinally of the machine. The member 252 has on its upper side two parallel ribs 255. Each of the blocks 246 is grooved on the under side for the reception of these ribs. Each block is held to the carrier by a screw 256 extending up through a slot 257 that extends throughout almost the entire length of the member 252. By reason of this construction the blocks, with their guide and gripping devices, may be adjusted into innumerable different positions transversely of the machine.

The saw is mounted in a suitable holder 260 having at the ends thereof, on opposite sides of the machine, diagonal slots 261. These slots preferably lie at an angle of forty-five degrees to the longitudinal axis of the machine. Stationary pins 262 rise from underlying portions of the

stationary base frame member of the machine into these slots and thus compel the saw to travel a diagonal path when it moves at all. I have found that this arrangement, which causes the saw teeth to cut across the ribbons at an angle of forty-five degrees, insures good, clean saw cuts in the ribbons.

5

The saw and the carrier for the combined guide and gripper units are both driven from a transverse shaft 263 at the front end of the machine. This shaft, as shown in Figs. 2 and 3, may be driven from the main shaft 27 by a sprocket chain 259. On the shaft 263, within the hollow base of the machine, are two cam disks 264, each having in one side thereof a continuous cam groove 265. (See Fig. 1.) Fixed to the member 252 are two connecting rods 266 each having at the front end a fork 267 straddling the shaft 263. The forks on these connecting rods may be similar to the fork 273 on the rod 274 to be hereafter described. On each fork is a cam roller 268 engaged in the cam groove in the corresponding disk 264. As the shaft 263 revolves, the ribbon and saw guide is moved through a working and a return stroke once during each revolution of the shaft 263; the time consumed by each part of the cycle depending upon the shape of the cams.

10

The shaft 263 has on one end thereof, outside of the machine, a third cam disk, 270, in the outer face of which is a continuous cam groove 271. (See Fig. 2.) Into this groove extends a cam roller 272 carried by a fork 273 on the forward end of a long connecting rod 274 having at its rear end a toothed section or rack 275; the fork 273 straddling the shaft and preventing the front end of the connecting rod from swinging up and down. The rod 274 extends rearwardly through a keeper 276 that may be a U-shaped member through the free ends of the arms of which a vertical shaft 277 extends. The shaft 277 is mounted in suitable upper and lower bearings 278, on the base member of the machine and has fixed thereon a toothed segment 279 which meshes with the teeth on the connecting rod 274. Fixed to the shaft 277, above the keeper 276, is a laterally-projecting arm 280 having therein a long slot 281 extending lengthwise thereof. Between the arm 280 and the saw blade holder 260 is a strut 282 one end of which is connected to the holder by a pin 283 while the other end is connected to the arm by a bolt 284 passing through the slot 281. In order that the strut shall be free to swing about both the pin 283 and the bolt 284, the saw blade holder 260 is preferably made bifurcated at the end to which the strut is attached and the arm 280 is made in fork form. The ends of the strut are therefore embraced by the saw blade holder and by the rocker arm, respectively, and neither the pin 283 nor the bolt 284 can exert any clamping pressure on the strut. However, the bolt 284 may be held fixed at any point along the slot 281 and thus insure that the saw will be driven through variable strokes of predetermined lengths determined by the distance between the bolt 284 and the shaft 277. In other words, by shifting the bolt along the slot 281 the depth of the saw cuts may be varied, but will remain the same as long as the position of the bolt is not changed.

15

In Figs. 12 and 13 I have shown a transverse rail 285 just in front of the ribbons or the ribbon positions. Such a rail may be provided, if desired, to back up the ribbons while the sheet A is advanced into the notches in the ribbons, al-

though I have not found it necessary to adopt this expedient. The position of the rail should, of course, be adjusted whenever a change is made in the ribbon width.

5 It will probably have been perceived that the saw cuts or notches are made in the ribbons just below the plane of the sheet A and that, accordingly, the notches which are to receive the end of this sheet are held slightly below this plane by 10 the now stationary ribbons while the sheet A advances. However, I have had no trouble in effecting the assembly of the ribbons and the advance end of the sheet A on this account. As there is no support for the front end of the sheet 15 A, unless it be the saw blade, for a substantial distance back from the front edge, it naturally tends to sink or sag a little and bring itself more nearly into registration with the notches in the ribbons when the saw blade is retracted. 20 Furthermore, if the sheet A is properly inserted in the machine, the tendency of paper unwound from a roll to curl up may be utilized to produce a slight natural downward curvature of the free advance end of the sheet and thus compensate 25 for the slight downward displacement of the notches in the ribbons. In case difficulty should be encountered from this source, because of the nature of the paper stock that is being employed or for other reasons, positive compensation for 30 the initial difference in levels between the notches in the ribbons and the horizontal sheet that must enter the notches may easily be provided. Thus in Fig. 1 I have shown at the top of the machine, just in front of the position of the vertically-hanging ribbons, a rocker device 290 adapted to swing about a transverse, horizontal axis. This device carries a small roller 291, also extending crosswise of the machine; the roller being close to the ribbons. On the shaft 263 is an eccentric 35 292. From the eccentric strap 293 on the eccentric, up to the rocker device, extends a rod 294. As the shaft 263 revolves, the rocker device is oscillated and the roller 291 is moved into and out of engagement with the vertical flight of 40 ribbons. By properly timing the parts so that the pressure of the small roller on the ribbons occurs while the sheet A is advancing to enter a set of notches in the ribbons, the ribbons being at this time firmly gripped between the now stationary feed rolls 92 and 93, there will be a slight bodily 45 lifting of the ribbons and a consequent raising of the notches therein which are about to receive the end of the sheet A.

In the description of the mechanisms mounted 50 on the vertically-movable frame 140 no mention was made of the means illustrated for taking up slack in the sprocket chain 157. As best shown in Fig. 3, it will be seen that the motor 151 is mounted on a platform 296 hinged at one end to the frame, as indicated at 297, whereas the other end is supported by screws 298. When the chain becomes loose, the screws may be turned in a direction to raise the corresponding end of the platform, thereby taking up the slack in the chain. 55 It should perhaps also be noted that the reason for driving three of the distributed pinion shafts directly from the motor is to avoid the heavy drag that occurs when a long train of pinions is driven from one end only, particularly where 60 many of the pinions carry loads.

All of the more important mechanisms have 65 now been fully described, whereas those containing little or no novelty have been described only so far as is necessary for an understanding of the manner in which the new features cooperate with 70

the old. Furthermore, the operations of the various mechanisms have been explained in connection with the description of their structural details and it is believed that no further detailed description of the operation of the machine as a whole will be useful; as it will be evident how the timing of the various mechanisms must be co-ordinated to move, work and assemble the materials into cell cases, and how various adjustments may be made to produce an almost infinite variety 10 of cell cases. By cell cases I mean, of course, structures composed of crossing, interlocked strips. In the simplest form there need be only two strips. Calling one of these two strips the longitudinal strip and the other the transverse 15 strip, it will be evident that the number of longitudinal and/or transverse strips in cell cases made in the machine may be varied over a wide range. So, also, the widths of the strips may be greatly varied as may be the lengths and widths of the 20 cells and the lengths of the buffers, by simply making the proper adjustments in the machine.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In a machine of the character described, means to form a ribbon and feed it lengthwise step by step, a saw, means to actuate the saw to cut notches into an edge of the ribbon at predetermined distances apart during periods of rest of the ribbon, and means to engage other short cross ribbons or strips in the said notches.

2. In a machine of the character described, means to form a ribbon and feed it lengthwise step by step, a saw, means to actuate the saw to cut notches into an edge of the ribbon during periods of rest of the ribbon, means to adjust the saw-actuating means to vary the depth of said notches, and means to engage other short cross ribbons or strips in the said notches.

3. In a machine of the character described, means to feed a plurality of ribbons lengthwise in parallel relation to each other and with their flat faces transverse to a plane intersecting all of the ribbons, a saw long enough to span all of the ribbons, means to actuate the saw to cut notches into corresponding edges of the ribbons, and means to engage a cross strip in such notches.

4. In a machine of the character described, means to feed a plurality of ribbons lengthwise in parallel relation to each other with their flat faces transverse to a plane intersecting all of the ribbons, a saw, means to actuate the saw to cut a notch in an edge of each ribbon, and means to engage a cross strip in said notches.

5. In a machine of the character described, means to slit a sheet into ribbons and feed them lengthwise in parallel relation to each other with their flat faces transverse to a plane intersecting all of the ribbons, means to cut notches in corresponding edges of the ribbons while they are in the aforesaid parallel relation to each other, and means to engage cross strips in such notches.

6. In a machine of the character described, means to slit a sheet into ribbons and intermittently feed the ribbons lengthwise in a vertical direction in parallel relation to each other with their flat faces transverse to a plane intersecting all of the ribbons, means to cut notches in corresponding edges of said ribbons after the forma-

tion of the ribbons, means to feed a sheet edgewise toward said ribbons and into said notches, a stationary member adapted to be adjusted into various different positions lengthwise of said ribbons, and feeding means and cutters for said ribbons carried by said member.

7. In a machine of the character described, means to slit a sheet into ribbons and intermittently feed the ribbons lengthwise in parallel relation to each other with their flat faces transverse to a plane intersecting all of the ribbons, a saw mounted beside the path of travel of the ribbons and facing corresponding edges of the latter, means to actuate the saw to cause it to cut notches 15 in the said edges of the ribbons and then be retracted into an idle position while the ribbons are at rest, and means to feed a sheet edgewise into said notches while the ribbons remain in the positions which they occupied at the time the 20 notches were cut.

8. In a machine of the character described, means to slit a sheet into ribbons and intermittently feed the ribbons lengthwise in parallel relation to each other with their flat faces transverse 25 to a plane intersecting all of the ribbons, a saw mounted beside the path of travel of the ribbons and facing corresponding edges of the latter, means to actuate the saw to cause it to cut notches in the said edges of the ribbons and then be retracted into an idle position while the ribbons are at rest, means to feed a sheet edgewise into 30 said notches while the ribbons remain in the positions which they occupied at the time the notches were cut, a stationary member adapted to be adjusted into various positions lengthwise of said 35 ribbons, shears for severing the ribbons along transverse lines, and means to adjust the shears bodily in the direction of the length of said ribbons.

40 9. In a machine of the character described, means to feed a ribbon lengthwise, a member having therein a slot opening through one end to receive and guide the ribbon, said member comprising two sections separable in a plane transverse to the direction of length of the ribbon, means yieldingly pressing said sections together, a saw adapted to cut an edge notch in the ribbon; means to actuate said member and said saw in such a manner that said member is 45 caused to embrace the ribbon, the saw is driven through a cutting stroke against the ribbon between and spreading apart the sections of said ribbon guide, and the guide and the saw are then caused to be retracted clear of the ribbon; 50 and means to feed a cross member into the notch in the ribbon cut by the saw.

55 10. In a machine adapted to form notched strips and interengage them with each other, comprising means to feed one strip-forming member intermittently, means to feed the second strip-forming member intermittently crosswise of the path of travel of the other member, shearing means to sever one of said members, a rotatable actuator for the shearing means, a 60 series of coaxial ratchet wheels fixed to the actuator and differing from each other in the numbers of their teeth, a driving member reciprocal in timed relation to one of the aforesaid feed means, a pawl operated by said driving member, and supporting means for the pawl adapting it to be engaged with any one of said ratchet wheels.

70 11. In a machine of the character described, two parallel members movable relatively to each other from and toward each other, a plurality of 75

dies distributed along one of said members, a plurality of punches distributed along the other member and adapted to enter the dies to punch holes in a sheet interposed between said members, a cutter element mounted on each punch so as to be movable crosswise of the same at an acute angle and adapted to enter the corresponding die, and means simultaneously to adjust the cutter elements in all of the punches.

12. In a machine of the character described, a feed roll means including a reciprocable bar to drive said roll, a member mounted to rock about an axis at right angles to a plane containing the long axis of the said bar, a connection between said bar and said member at a point remote from the rocking axis of the latter, a second member rotatable about an axis parallel to the aforesaid axis, the first member having a radial channel displaced angularly with respect to the connection between the bar and that member, a crank pin on the second member engaged in said channel, and means to rotate said second member.

13. In a machine of the character described, a main frame, means on the main frame to punch and feed a horizontal sheet to an assembly point, means on said main frame to slit a second sheet into ribbons and feed such ribbons downwardly to said assembly point, means on said main frame to cut notches in the edges of said ribbons, a 25 vertically-adjustable auxiliary frame, and means on the latter frame to feed and guide the ribbons and sever them transversely.

30 14. In a machine of the character described, a frame, a row of spaced parallel feed rollers occupying fixed positions, a supporting member extending parallel with and lengthwise of said row of rollers, combination guide and shear units mounted on said member so as to be adjustable lengthwise of the row of rollers, elements each long enough to span the distance between one of said units and said row of rollers, each element being hinged at one end to one of said units so as to be capable of swinging about an axis parallel to said rollers, and a feed roller rotatably 45 mounted on the other end of each of said elements and adapted to be inserted in the gap between two of the fixed rollers above the corresponding guide and shear units and cooperate with one of them.

50 15. In combination, a cell-forming material-feeding means including two drives each adapted to feed step by step and the steps being of different lengths for the two drives, a device to render operative or inoperative at will that drive which produces the longer steps, a controller for said device, shear means for the material, a controller for said shear means, a common actuator for said controllers, and means to supply other cell-forming material and interengage it with 55 the aforesaid material.

60 16. In a machine of the character described, means to intermittently feed a plurality of ribbons lengthwise in substantially parallel relation to each other with their flat faces transverse to a plane intersecting all of the ribbons, means to cut notches in corresponding edges of the ribbons while they are at rest in said parallel relation, and means to feed a cross member into said notches while the ribbons remain in the positions they occupied at the time said notches were 65 cut.

70 17. In a machine of the character described, two supporting members movable relative to each other from and toward each other, a die carried 75

by one of said members, a punch carried by the other member and adapted to enter said die to punch a hole in a sheet interposed between said members, and a cutter element associated with each punch so as to be adjustable crosswise of the punch at an acute angle and adapted to enter said die.

18. In combination, a cell-forming material-feeding means including two drives each adapted to feed step by step and the steps being of different lengths for the two drives, a device to render operative or inoperative at will that drive which produces the longer steps, and means for controlling said device comprising a rotatable actuator, a series of coaxial ratchet wheels connected with the actuator and differing from each other in the number of their teeth, a pawl adapted to selectively cooperate with any one of said

ratchet wheels, means for oscillating the pawl, and means to supply other cell-forming material and interengage it with the aforesaid material.

19. In combination, a cell-forming material-feeding means including two drives each adapted to feed step by step and the steps being of different lengths for the two drives, a device to render operative or inoperative at will that drive which produces the longer steps, electrically operated means for actuating said device, means for energizing said means, a series of ratchet wheels for operating said energizing means and differing from each other in the number of their teeth, and means selectively engaging any one of said ratchet wheels for turning them at periodic intervals. 5 10 15
